UNITED STATES PATENT OFFICE.

FRED ELLIS, OF ST. LOUIS, MISSOURI, ASSIGNOR TO UNITED SHOE MACHINERY COMPANY, OF PATERSON, NEW JERSEY, A CORPORATION OF NEW JERSEY.

HOLDDOWN.

1,138,855.

Specification of Letters Patent. Patented May 11, 1915.

Application filed July 12, 1912. Serial No. 709,031.

To all whom it may concern:

Be it known that I, FRED ELLIS, a citizen of the United States, residing at St. Louis, in the State of Missouri, have invented certain Improvements in Holddowns, of which the following description, in connection with the accompanying drawings, is a specification, like reference characters on the drawings indicating like parts in the several figures.

This invention relates to hold-down devices for use in connection with bed lasting machines, such, for example, as the well-known commercial Ideal lasting machine which is shown in the United States patent to Grandy No. 552,834, to which reference may be had for a description of the machine in general.

The present invention is embodied in an improved form of hold-down foot. Preferably and as shown, the hold-down foot comprises a plate which is of substantially the shape of the toe portion of an innersole and is adapted to fit closely against the rear face 25 of the raised lip or rib which exists on the innersole of a welt shoe, said plate being adapted to sustain the rib against the lateral pressure of the toe lasting wipers as they are operated for working the upper into the 30 angle formed by the feather and rib of the innersole.

As another feature of the invention, the rib engaging portion of the foot plate is formed by the edge of the plate only which 35 is shown as turned downwardly at an angle to the plane of the sole to form a flange and is dressed off so as to rest evenly against the face of the innersole, preferably with a substantial space between the face of the inner- 40 sole and the body of the plate. This formation of the hold-down foot plate adapts it for use also as a feather clamp. In such use it is positioned first forwardly of, or outside of, the rib and upon the feather edge of 45 the innersole where it maintains the feather down on the last so as to reduce danger of the feather being caught by the wipers in their upward movement and lifted away from the last bottom. The comparative

thinness of the down-turned edge or flange 50 portion of the plate in engagement with the feather enables the wipers to be forced in over the edge of the last and over the feather of the innersole sufficiently far to hold firmly the upper in lasted position before the 55 hold-down plate is withdrawn from engagement with the feather. When this is done, the wipers may be advanced farther to crowd the upper into the angle and into position to be secured by wiring or otherwise. When 60 the plate is withdrawn from the feather and prior to this further movement of the wipers the plate may be again positioned behind the innersole rib to support it during the final inward movement of the wipers. 65

As I am advised, it is new with me to provide a hold-down foot which is constructed and arranged so that it can be used alternatively or successively outside of a welt innersole lip or rib as a feather clamp extending around the curved end of the toe or inside the rib as an abutment to resist lateral pressure against the rib at one or both sides as well as at the tip of the toe end of the innersole. 70

The outside edge contour of the hold-down foot approximates closely the edge contour of the corresponding portion of the wipers, and another advantageous use of this foot is as a binding wire seat crease former in co- 75 operation with the wipers. In this use the foot is positioned upon the feather just outside the innersole rib and, it being thin, the wipers are advanced and mold the upper against the outer face of the foot to produce 80 the wire seat crease. The foot being substantially rigid, as compared with the rib of the innersole, the crease is more definitely formed than it has heretofore been formed between the wipers and the rib. The wipers 85 are then backed away slightly from the crease thus formed to allow the binding wire to be placed in the seat for it and to permit the foot to be withdrawn from the feather and positioned inside the rib where it may 90 serve as an abutment for the rib. The wipers can then be again advanced to engage the 95 wire and press it into its seat crease and there-

after, and here is one of the important advantages for this feature of the invention, to force the seat crease inwardly toward and against the innersole rib and thus substantially tighten the upper. This action is particularly advantageous at the sides of the tip of the toe, or the corners of the toe, where it is most difficult to overwork the upper without wrinkles or looseness.

As a further feature of this invention, with which may or may not be used the foregoing features, the foot plate which constitutes the pressing member of the hold-down is supported for lateral movements of adjustment or adaptation to the work on an arm which is movable over the bottom of a shoe sustained in position to be lasted in the machine. There is a pivotal connection between the foot plate and the supporting arm which is preferably located so that it will be over substantially the center of curvature of the toe end of the innersole when the foot plate is in operative position. By this adjustable mounting the foot plate may be swung toward one side or the other side of its supporting arm to enable it to fit innersoles for right and left crooked lasts having toes of approximately symmetrical curvature. It is most important that the foot plate form an abutment for the innersole rib at the outer side of the toe because it is at this side of the toe that most difficulty is experienced in properly lasting the upper firmly against the rib. Therefore, while the foot plate may most advantageously be made to fit the shoe exactly and be changed for different sizes of the same style of last, the same foot plate, mounted as herein described, may be used with very satisfactory results for larger shoes than it accurately fits, this being done by positioning and swinging it over against the rib at the outer side of the toe of the right or left shoe which happens to be in the machine. To make this clear this use of the hold-down foot is illustrated in the accompanying drawings.

This invention is particularly advantageous when used with machines of the Ideal type above referred to in which the alignment of the toe and heel heads and of the wipers carried thereby is fixed, and consequently the longitudinal median line of the forepart of a last which has considerable swing will extend at a substantial angle to the line connecting the center of the toe head, or the toe wipers, with the center of the heel head, or the heel seat wipers, the said median line extending to one side of the line joining the end centers of the last for a right shoe and to the other side for a left shoe. Means for limiting the movement of the plate about its pivot is preferably provided and may conveniently take the form of a slot and pin connection, the slot being formed in the plate

and being struck from the pivot of the plate as a center and a headed pin being passed through the slot and secured to the supporting arm to co-act with the ends of the slot for limiting the movement of the plate in either direction.

These and other features of the invention will appear more fully from the following detailed description in connection with the accompanying drawing, and will then be 75 more definitely pointed out in the claims.

Figure 1 is a plan view of a lasting machine of the Ideal type as disclosed in the patent above referred to provided with the preferred embodiment of the invention; 80 Fig. 2 is a perspective view, partly in section, showing the manner of attaching the hold-down foot to the hold-down arm, the foot and its supporting arm being shown by full lines detached from their swinging 85 carrier, and by dotted lines in operative position; Fig. 3 is a longitudinal section of the forepart of a shoe showing in side elevation the hold-down foot applied thereto:

In Fig 1 which is a plan view of a machine of the "Ideal" type, the heel and toe heads are represented at A and B, respectively, the longitudinal axis of the machine passing centrally through them both. The character 2 indicates the swinging carrier 90 by which the hold-down foot 30 and its supporting arm 20 are moved over the bottom of the shoe sustained in position to be lasted in the machine. The hold-down carrier is mounted to swing on a post 1 and has a 100 vertical movement with the post. This post constitutes the operating means for the hold-down and with it is connected a usual actuating treadle and a return spring, and preferably also a locking latch as shown 105 for example in British Patent No. 19,512, 1911. The hold-down foot 30 which is connected to the arm by complementary formation of any suitable character permitting lateral swinging movement of the foot 110 about pivot 32. Such movement is limited, and the foot plate is further secured to the arm 20, by a headed stud 36 and curved slot 34 connection between the arm and the plate in the rear of the pivot 32, the slot 115 being curved in an arc about said pivot 32.

The hold-down foot is shaped to fit closely against the innersole rib at the tip of the toe and is contoured to form an abutment for the inner face of the rib both at the tip and at one or both sides of the tip of the toe for supporting said rib against the action of the lasting wipers. The hold-down foot is advantageously hollowed on its work engaging lower face thus affording 120 a concentrated bearing of its edge upon the innersole closely adjacent to the innersole rib and unaffected by irregularities in the surface of the middle portion of the innersole. As shown, this foot comprises a plate 125

5 stamped out of stiff sheet metal and has its edges bent at the front end and sides to form a down turned flange 31. This formation permits the foot plate to be applied either with its bearing flange inside the innersole rib as shown in the drawings or outside of said rib where it will press down upon the feather of the innersole to prevent the feather from being lifted by 10 the wipers. If the shoe is large for the foot plate, as will in practice often be the case, the foot plate is made to abut against the rib at the tip of the toe and is swung into engagement with the rib at the outer side 15 of the toe, as shown in the drawings, where the rib most requires support. In Fig. 1 the foot plate 30 is shown in the position it would assume upon a right shoe, the right shoe being shown in full lines in that figure 20 in which the swing of the last is indicated by the line $x-R$ which is the longitudinal median line of the forepart extended. In dotted lines in the same figure is represented the outline of the left shoe, the longitudinal median line of the forepart of which extends in the direction of $x-L$. It will be seen that the line $x-R$ is inclined toward the axis from the other side and that considerable movement of the plate 30 is 25 required to enable it to fit closely the toe portion of a right or left shoe where the swing of the last is considerable. To provide this movement the plate 30 is pivoted to the arm 20 at 32, which point is substantially at the center of curvature of the extreme toe portion of the plate. The plate 30 being freely pivoted at this point automatically assumes a position against the rear face of the rib of the innersole when 30 pushed forward against it by rotation of the carrier 2 about the vertical axis 1. The arm 20 which supports the hold-down plate 30 is preferably resilient and the stud 4 by which it is pivotally attached to the arm 2 35 has a roughened head 6, Fig. 3, which is adapted to engage the innersole when the engagement of the plate 30 with the shoe has caused the arm 20 to yield. The stud 4 is flattened on its sides at 8 and is maintained in fixed position in a hole in the arm 2 by a spring-held pin 10 which is forced outwardly into a hole 12 in the stud. The stud 45 is passed through a plate 14 having lips 16 bent up at the edges thereof. The arm 20 is provided at one end with a hole 22 having an open slot 24 leading therefrom and is assembled upon the end of the hold-down arm by pushing the slotted end upon the stud in the direction of the flattened sides 50 of the stud until the stud rests in the opening 22 when the arm 20 may be rotated about the stud. The lips 16 of the plate 14 are arranged to rest against opposite sides of the arm 20 and by reason of the 55 tapered formation of the arm 20, Fig. 1, it

cannot be pulled from the stud even when in line with the flattened sides thereof until it has been sprung over the lips 16.

For different styles of shoes different hold-down feet may be provided, the construction shown providing means for readily detaching one foot and its arm 20 and attaching another. To effect this the operator has only to insert a pointed instrument between the plate 14 and the spring arm 20 and separate them sufficiently to disengage the lips 16 from the arm 20 so that the plate 14 and arm 20 may be swung relatively to each other about the stud. The arm 20 may then be detached by rotating 75 it into alignment with the hold-down arm, Fig. 2, and pulling it outwardly in the direction of said arm, the flattened sides of the stud then permitting it to pass through the slot 24 of the arm 20. Other hold-down 80 feet may be attached to the hold-down arm by reversing the movements described for removing the foot.

The use and operation of the described embodiment of the invention may be readily 90 understood by those skilled in the art without further description; and it is also apparent that various modifications of the device as described may be made without departing from the invention.

Having described my invention, what I claim as new and desire to secure by Letters Patent of the United States is:—

1. A hold-down having a foot plate arranged substantially parallel to the plane of the last bottom and provided on its end and lateral edges with a depending flange constituting the innersole engaging face and shaped to fit a welt innersole back of the rib for supporting the rib against the advancing and closing action of toe lasting 105 wipers.

2. A hold-down having a foot plate provided on its end and lateral edge with a turned down flange constituting the innersole engaging face and shaped to fit a welt innersole back of the rib, said plate presenting a recess back of and inside the down-turned edge to permit the said edge to be positioned in front of the innersole rib and 115 upon the feather for use in clamping the feather upon the last bottom without crushing the lip.

3. A hold-down having a foot plate provided on its end and lateral edge with a turned down flange constituting the innersole engaging face and shaped to fit a welt innersole back of the rib, said plate being mounted for movement lengthwise of the shoe to permit it to be used first as a feather 125 clamp in front of the innersole rib and then as a rib backing in the rear of said rib.

4. A hold-down having a foot plate hollowed to form a marginal edge face constituting the innersole engaging face and 130

shaped to fit a welt innersole back of the rib and supported for movement about substantially the center of curvature of the toe for adjustment to right and left crooked 5 shoes.

5. A hold-down for lasting machines comprising supporting and operating means and a foot plate hollowed on the work engaging face to form an acute angled marginal edge 10 of substantially the edge contour of the channel rib around the toe and along the side of the toe of a welt shoe innersole serving to concentrate its pressure on a line adjacent to said rib.

15. 6. A hold-down for lasting machines comprising supporting and operating means adapted to extend substantially to the center of curvature of the toe of the shoe to be lasted and a foot plate supported thereon 20 for movement about an axis located substantially at said center of curvature of the toe for adjustment to the ribs of welt shoe innersoles for right and left crooked lasts and having relatively straight rearward 25 extensions to support the rib at the sides of the toe of said innersole.

7. A hold-down for shoe lasting machines comprising supporting and operating means and a foot plate, complementary connecting 30 formations on said means and said plate arranged to permit a limited rotary movement of the plate on the supporting means laterally of the shoe and in substantially the plane of the shoe sole to enable the plate to 35 fit differently shaped toes of right and left crooked lasts.

8. A hold-down for lasting machines comprising supporting and operating means, and a foot plate mounted thereon, said foot 40 plate being shaped substantially to the con-

tour of the space inside the rib at the toe portion of the innersole of a welt shoe to be lasted and connections between said foot plate and said means permitting the plate to be moved for positioning it to form an 45 abutment against the inner side of the rib of the innersole on the outer side of a crooked right shoe and to be moved for differently positioning it to form an abutment against the inner side of the rib at the 50 outer side of a crooked left shoe.

9. A hold-down having a foot plate provided on its end and lateral edge with a downwardly projecting marginal innersole 55 engaging face and shaped to fit a welt innersole back of the rib, and a support to which said plate is pivotally connected near its front end and with which it has a pin and curved slot connection back of its front end, 60 substantially as described.

10. A hold-down foot plate and a support upon which it is pivoted near the front end of the plate and with which it has a guiding connection back of its front end permitting movement about said pivot for adaptation to 65 right and left crooked shoes.

11. A hold-down for lasting machines comprising a foot plate formed to present a narrow innersole engaging face and constructed and arranged to concentrate the 70 pressure of the foot plate along a narrow line immediately inside the channel lip of a welt shoe innersole.

In testimony whereof I have signed my 75 name to this specification in the presence of two subscribing witnesses.

FRED ELLIS.
